UNITED STATES PATENT OFFICE.

JAMES ROW, OF LONDON, ENGLAND.

SLEEPING OR MILITARY VALISE.

1,247,882. Specification of Letters Patent. Patented Nov. 27, 1917.

Application filed July 16, 1917. Serial No. 180,259.

To all whom it may concern:

Be it known that I, JAMES Row, a subject of the King of Great Britain and Ireland, residing at 24 Drury Lane, London, England, have invented a new and useful Sleeping or Military Valise, of which the following is a specification.

The present invention comprises an improved sleeping or military valise or one man tent and has the following advantages over existing valises:—perfect ventilation and greater comfort for the occupant, efficient protection for the upper part of the body in all conditions of weather, allows for full freedom of movement of the occupant, has no loose parts, is easily pitched and struck, has provision for holding toilet requisites, books or other small articles, and rolls up into a compact form for transport.

20 A valise constructed according to the present invention comprises essentially a foundation sheet forming a ground sheet, two side sheets each of which is attached to one of the longitudinal edges of the foundation sheet and is adapted to fold over said foundation or ground sheet, an end part attached to the head end of the foundation sheet and provided with ventilating means, a hood therefor, stretcher bars for holding the end part extended laterally and a pole and guy line for holding it extended vertically, a pocket formed at the foot end of the foundation sheet for the feet of the occupant, a flap—extending approximately 30 half the length of the foundation sheet and of a greater width than the latter—permanently secured to the end part and one side of the foundation sheet and adapted to be readily fastened by its opposite side to the opposite side of the foundation sheet, and means for fastening the foundation sheet on the ground and the side sheets and flap in position.

35 In the accompanying drawing illustrating this invention

Figure 1 is a view in side elevation of the valise erected and fastened together as if in use,

Fig. 2 is a view in plan thereof,

Fig. 3 is an end view showing the flap, thrown back and the side sheets thrown open, viewed from the foot end, and

Fig. 4 is an enlarged detail view.

Throughout the views similar parts are marked with like letters of reference.

The foundation sheet forming a ground sheet *a* has attached to its longitudinal edges two side sheets *b*, *c*, the one sheet *c* first folds over the sheet *a* and the sheet *b* is then folded over the sheet *c* when in use. 60 The end part *d* is attached at its lower edge to the sheet *a* and is also attached at its sides to wing pieces *b*¹, *c*¹, which form at the sides continuations of the side sheets *b*, *c*. The end part *d*—preferably shaped 65 as shown—is cut away at its upper part and a gauze material *d*¹ is inserted therein to allow for free ventilation. A hood *e* is provided on the exterior of the end part *d* to mask the ventilating openings and prevent 70 the ingress of rain. Stretcher bars or battens *d*² inclosed in pockets in the material from which the end part *d* is made are provided to keep the said part extended laterally and so give the required shape to the 75 tent when pitched. On the inner surface of the end part *d* pockets *d*³ are provided for toilet requisites, books or other small articles.

The foot end of the ground sheet *a* is 80 formed with a pocket *a*¹ for the feet of the occupant and the sheets *b* and *c* are provided with flaps *b*², *c*², at the foot end thereof. Provision is made for securing the parts together such as buckles and straps *b*³. 85

A flap *f* extending approximately a third to a half the length of the ground sheet from the head end is permanently secured to the end part *d* and along one side *f*¹ to the wing piece *b*¹. The opposite side is provided 90 with a narrow flap *f*² adapted to be fastened to the wing piece *c*¹ by press studs *f*³ or the like. This flap *f* is made sufficiently wide or full, particularly along its free edge *f*⁴, to allow plenty of room for the occupant to 95 turn over or sit up within the tent.

The edge *f*⁴ may be temporarily secured to the ground sheet *a* and side sheet *b* by suitable straps, eyes and fastenings *f*⁵ and at its center to the side sheet *b* by an eye 100 thereon and tapes *f*⁶ or the like. It will be understood that all these fastenings can be conveniently and readily operated from within by the occupant.

The ground sheet *a* is provided along its 105 edges with eyelets by which it is secured to the ground by pegs *a*². These pegs, which are attached by cords at convenient points of the parts forming the valise, are held when not in use within pockets such as *a*³. 110

The end part *a* is extended vertically and held in such extended position by a pole *g* the lower end of which is provided with a spike *g*¹ which is adapted to pass through 5 an eyelet in the ground sheet *a*. The upper end of the pole *g* has a socket *g*² to receive a spike on the terminal *g*³. The spike *g*¹ is first passed through the eyelet in the ground sheet and the upper part of the pole 10 is passed up under the hood *e* and through an opening at the top thereof, the spike on the terminal *g*³ is then passed through an eyelet *d*⁸—in top of the part *d*—into the socket *g*² in the pole. A guy line *h* permanently attached to the terminal *g*³ is passed 15 down outside the hood and then through a hole on the lower edge therein and then passes through a straining or clamping bar *h*¹ to which the free end is attached after 20 passing through the eye of the peg *h*² driven into the ground.

The pole *g* is loosely secured to the end part *d* by means of a swivel *g*⁴ (see Fig. 4 which is a part view of the end part with 25 the hood *e* removed) so as to allow of movement of the pole—within limits—in every direction and yet be always permanently secured to the part *d*. In Fig. 4 the pole *g* is shown in position to allow of the valise 30 being rolled up for transport. To pitch the tent after the end part *d* has been set up the foundation or ground sheet *a* is stretched out and pegged down and then the whole pulled up tightly by means of the guy line *h*. 35 The ground sheet *a* may be provided with a woolen lining adapted, when stuffed with hay or the like, to form a mattress, similarly an additional lining or pocket in the head end of the ground sheet may be provided to serve as a pillow when stuffed with 40 hay or the like.

What I claim and desire to secure by Letters Patent is:—

1. A sleeping valise comprising a ground 45 sheet, two side sheets, each of which is attached to one of the longitudinal edges of the ground sheet and is adapted to fold the one over the other and over the ground sheet, an end part attached to the head end 50 of the ground sheet and provided with ventilating means, a hood therefor, battens within said end part for holding it extended laterally, and a pole and guy line for holding it extended vertically, and a flap permanently 55 secured to the end part and one side of the ground sheet and adapted to be readily fastened by its opposite side to the opposite side of the ground sheet, as set forth.

60 2. A sleeping valise capable of being car-

ried in a rolled up form comprising a ground sheet, two side sheets attached to the longitudinal edges of the ground sheet the one sheet being adapted to fold over the ground sheet and the other sheet to fold 65 over both sheets, wing pieces attached to the ground sheet and forming side continuation pieces of the side sheets, an end part attached at its lower edge to the head of the ground sheet and at its sides to the wing 70 pieces, ventilating means in said end part, a hood masking said ventilating means and carried by the end part, means for keeping the end part extended laterally and stretched vertically, a flap permanently secured to the end part and one side of one 75 of the wing pieces and adapted to be readily fastened by its opposite edge to the other wing piece, and means for detachably fastening the various parts to each other, as 80 set forth.

3. A sleeping valise capable of being carried in a rolled up form, comprising a ground sheet, two side sheets attached to the longitudinal edges of the ground sheet, the 85 one sheet being adapted to fold over the ground sheet and the other sheet to fold over both sheets, wing pieces attached to the ground sheet and forming side continuation sheets of the side sheets, an end part at- 90 tached at its lower edge to the ground sheet and at its side to the wing pieces, a gauze material inserted within a cut away part in the end part for ventilation, a hood carried by the end part and masking the gauze part 95 therein, battens permanently secured to the end part to keep it extended laterally, a pole loosely but securely carried by said end part and adapted to hold it extended vertically, a guy line, peg and stretching means 100 for keeping said pole in its vertical position, a flap permanently secured to the end part and one of the side wing pieces and adapted to be readily fastened by its opposite edge to the other side wing piece, a 105 pocket formed in the foot end of the ground sheet for the feet of the occupant, pockets formed on the inner side of the end part, straps and fastenings for detachably holding the sheets and flap together, pegs for 110 holding down the ground sheet carried by cords secured to the valise, and pockets in the valise to hold the pegs when not in use, as set forth.

In testimony whereof I have signed my 115 name.

JAMES ROW.
